CAR ROOF

Charles David Bonsall, Pittsburgh, Pa., assignor
to P. H. Murphy Company, New Kensington,
Pa., a corporation of Pennsylvania

Application July 6, 1931, Serial No. 548,954

13 Claims. (Cl. 108—54)

This invention relates to metal car roofs of the kind shown in my copending application Serial No. 527,991, filed April 6, 1931, wherein the roof sheets form a series of ribs alternating with channels and have their adjacent margins connected by upstanding seams that are located within the channels, and the roof covering as a whole functions mechanically after the manner of a beam. The principal object of the present invention is to enable the roof ribs to cooperate efficiently with the roof seams in taking care of vertical load. Another object is to utilize the means by which the ribs are harnessed to the seams as tie and strut members between the seams and as load-lifting beams. Other objects are simplicity and cheapness of construction, and compactness of design. The invention consists in the parts, arrangements and combinations of parts hereinafter described and claimed.

20 In the accompanying drawing, which forms part of this specification and wherein like symbols refer to like parts wherever they occur,

Fig. 1 is a plan view of a portion of a car roof embodying my invention,

25 Fig. 2 is a transverse section through one-half of the roof on the line 2—2 in Fig. 1,

Fig. 3 is a vertical longitudinal section through the roof at the ridge on the line 3—3 in Fig. 1; and

30 Fig. 4 is a vertical cross-section on the line 4—4 in Fig. 3.

Referring to the accompanying drawing, my invention is shown in connection with a car roof comprising metal roof sheets 1 that extend from side plate 2 to side plate 2 of the car and are riveted or otherwise rigidly secured thereto. The roof sheets are adapted and arranged to form series of flat-topped ribs A alternating with flat-bottomed channels B, and are rigidly connected along their adjacent margins by upstanding seams C located within the channels. The ribs A and the channels B extend from side plate 2 to side plate 2, the ribs merging at or near the eaves ends of the roof sheets into the plane of

45 the bottoms of the channels. The longitudinal middle portions of the roof sheets are offset upwardly with respect to the side marginal portions thereof to form the ribs A; and the side marginal portions of adjacent sheets form the bottoms of the channel B. The seams C, which function as outside carlines, are formed by upstanding flanges 3 along the adjacent side margins of the roof sheets and by inverted U-shaped caps that straddle said flanges and are rigidly secured thereto by rivets 5. The seam caps 4 are pro-

vided with outstanding base flanges 6 that rest on the bottoms of the channels B and are bent down at the eaves and riveted to the side plate 2. By this arrangement, the upstanding seams C are located at the middle of the channels B substantially between the upper and lower levels of the roof; and the rivets which secure said seam caps to said flanges are located wholly outside of the car where they are easy to drive and where they produce no danger of leakage into the car.

Adjacent seams C are connected together preferably at the ridge by members so arranged that the structure as a whole acts after the manner of a beam extending between adjacent 70 seams. As shown in the drawing, each of said beams comprises upper and lower members or sections 7 and 8, respectively, that extend from seam to seam above and below the roof sheets with their ends rigidly secured to the opposing base flanges 6 of the seam caps 4 of adjacent seams by means of rivets 9. Each section of the beam preferably comprises a channel with outstanding flanges at the lower edges of its side walls, the upper section 7 being offset upwardly, as at 10, intermediate its ends so as to straddle the roof rib A located therebelow, and the lower section 8 being straight and preferably being made long enough to extend beneath several roof ribs. The upper and lower sections 80 of the beams are connected by means of strut members 11 located beneath the roof ribs adjacent to the sides thereof. Each of the strut members 11 preferably comprises a channel-shaped member located between the top of the lower section 8 and the underside of the roof rib. The channel-shaped strut 11 is disposed cross-wise of the beam sections with its web riveted flatwise to the top of the lower section and is provided with outstanding flanges at the 95 top of its side walls that are riveted to the underside of the roof rib by rivets 12 that pass through the top wall of said rib and the base flanges of said upper section.

By the arrangement described, adjacent roof 100 seams are rigidly connected together by members that serve as ties and struts to prevent said seams from tilting or bowing. These seam connecting members also serve as beams to distribute the vertical load applied thereto between adjacent 105 seams; and they also serve to harness the roof ribs to said seams, thereby causing said ribs to cooperate with said seams in supporting such load. The strut members 11 that connect the upper and lower sections 7 and 8 of the beam 110

- also serve to hold the top of the roof rib against the upwardly offset portion 10 of the upper section and thus resist the tendency for the rib to buckle or pull away from said upper section.
- 5 The beams not only serve to stiffen and strengthen the roof; but they also serve as load-lifting beams to which lifting tackle or devices may be secured, such devices being adapted to be supported on the outstanding base flanges of 10 the lower sections 8 of the beams.

What I claim is:

1. A single-course car roof comprising roof sheets rigidly connected along their adjacent margins by upstanding seams, and a beam extending 15 between adjacent seams and rigidly secured thereto, said beam comprising upper and lower sections and struts between the middle portions thereof, the ends of said sections being secured together and to the roof sheets.
- 20 2. A single-course car roof comprising roof sheets having cooperating seam flanges along their adjacent margins, seam caps that straddle said seam flanges and are rigidly secured thereto, and beams extending between adjacent seam caps with their ends rigidly secured thereto, each of said beams comprising upper and lower sections that span from seam cap to seam cap, and struts between the middle portions of said sections.
- 25 3. A single-course car roof comprising roof sheets having cooperating seam flanges along their adjacent margins, seam caps that straddle said seam flanges and are rigidly secured thereto, and beams extending between adjacent seam caps with their ends rigidly secured thereto, each of said beams comprising upper and lower sections that span from seam cap to seam cap above and below the roof respectively, and struts between the middle portions of said sections.
- 30 4. A car roof comprising roof sheets having upstanding flanges along their adjacent margins, seam caps that straddle said flanges and are rigidly secured thereto, and beams extending between adjacent seam caps with their ends rigidly secured thereto, each of said beams comprising upper and lower sections that span from seam cap to seam cap, the upper section being offset upwardly between seams and struts between the lower section and the offset portion 45 of the upper section.
- 45 5. A car roof comprising roof sheets having upstanding flanges along their adjacent margins, seam caps that straddle said flanges and are rigidly secured thereto, and beams extending between adjacent seam caps with their ends rigidly secured thereto, each of said beams comprising upper and lower sections that span from seam cap to seam cap, the upper section being located above the roof sheets and the lower section being located beneath said roof sheets, the upper section being offset upwardly between seams, and struts between the lower section and the offset portion of the upper section.
- 50 6. A car roof comprising roof sheets having upstanding flanges along their adjacent margins, seam caps that straddle said flanges and are rigidly secured thereto, said roof sheets being provided intermediate said seams with upstanding ribs, and beams extending between adjacent seam caps with their ends rigidly secured thereto, each of said beams comprising upper and lower sections that span from seam cap to seam cap, the upper section being located above the roof sheets and the lower section being located beneath said roof sheets and the lower section being lo-

cated beneath said roof sheets, said upper section being offset upwardly intermediate its ends conformably to said rib so as to straddle and reinforce the rib of the roof sheet located therebelow.

7. A car roof comprising roof sheets having upstanding flanges along their adjacent margins, seam caps that straddle said flanges and are rigidly secured thereto, and beams extending between adjacent seam caps with their ends rigidly secured thereto, each of said beams comprising upper and lower sections that span from seam cap to seam cap, the upper section being located above the roof sheets and the lower section being located beneath said roof sheets, said upper section being offset upwardly intermediate its ends, and strut members interposed between the lower beam section and the upwardly offset portion of the upper section.

8. A car roof comprising roof sheets having upstanding flanges along their side margins, seam caps straddling said flanges and rigidly secured thereto, said roof sheets being provided between seam caps with upstanding ribs, and members located above said sheets and extending from seam cap to seam cap and rigidly secured thereto and to the tops of said ribs and having upwardly offset portions fitting said ribs and straddling and reinforcing said upstanding ribs.

9. A car roof comprising roof sheets having upstanding flanges along their side margins, seam caps straddling said flanges and rigidly secured thereto, said roof sheets being provided between seam caps with upstanding ribs, members located outside the roof and extending from seam cap to seam cap and rigidly secured thereto and having upwardly offset portions straddling said roof ribs, and means for securing said roof ribs to the upwardly offset portions of said members.

10. A car roof having alternating flat-topped ribs and flat-bottomed channels formed therein extending cross-wise of the car, said roof consisting of a plurality of roof sheets that have their adjacent margins connected by upstanding seams located within and extending longitudinally of said channels, and beams extending longitudinally of the roof from seam to seam, said beams being rigidly secured at their ends to the seams and intermediate their ends to the sheets and being offset upwardly intermediate their ends to fit said ribs and prevent spreading thereof.

11. A car roof having alternating flat-topped ribs and flat-bottomed channels formed therein extending cross-wise of the car, said roof consisting of a plurality of roof sheets that have their adjacent margins connected by upstanding seams located within and extending longitudinally of said channels, beams extending longitudinally of the car between seams with their ends rigidly secured thereto, said beams comprising sections that are located above the roof sheets and are offset upwardly conformably to said ribs to straddle and reinforce said ribs, and a lower section located below the roof sheets and extending straight from seam to seam but secured to said upper section at intervals.

12. A car roof having alternating flat-topped ribs and flat-bottomed channels formed therein extending cross-wise of the car, said roof consisting of a plurality of roof sheets that have their adjacent margins connected by upstanding seams located within and extending longitudinally of said channels, beams extending longitudinally of the car between seams with their ends rigidly secured thereto, said beams comprising upper

sections that are located above the roof sheets and are offset upwardly to straddle said ribs, a lower section located below the roof sheets and extending straight from seam to seam, and strut members interposed between the top of the straight beam section and the undersides of the ribs and rigidly secured thereto and to the sections located above said ribs.

13. A single-course car roof comprising roof sheets rigidly connected along their adjacent

margins by upstanding seams, and a beam extending between adjacent seams and rigidly secured thereto, said beam comprising upper and lower sections located respectively above and below said roof sheets and means whereby said sections are rigidly secured together at their ends and middles, said means including rivets which extend through the roof sheets.
